UNITED STATES PATENT OFFICE.

WILLIAM F. WILMOTH, OF NEW YORK, N. Y., ASSIGNOR TO AMERICAN FURNACE COMPANY, OF NEW YORK, N. Y., A CORPORATION OF NEW YORK.

STEAM-BOILER OR OTHER FURNACE.

SPECIFICATION forming part of Letters Patent No. 702,756, dated June 17, 1902.

Original application filed October 18, 1901, Serial No. 79,176. Divided and this application filed March 5, 1902. Serial No. 96,851. (No model.)

To all whom it may concern:

Be it known that I, WILLIAM FRANKLIN WILMOTH, a citizen of the United States, residing in New York, in the county and State 5 of New York, have invented certain new and useful Improvements in Steam-Boiler or other Furnaces; and I do hereby declare the following to be a full, clear, and exact description of the invention, such as will enable others 10 skilled in the art to which it appertains to make and use the same.

My invention relates to improvements in steam-boiler and other furnaces; and it consists in the novel means employed for admitting air to the furnace and heating such air before contact thereof with the furnace-gases and in the novel construction of an arch over the furnace.

The present application for Letters Patent 20 is a division of one filed by me on October 18, 1901, Serial No. 79,176.

The objects of my invention are to increase the efficiency of boiler and other furnaces, to avoid the production of smoke when using 25 bituminous coal and other smoke-producing fuel, to heat efficiently the air supplied to complete the combustion without decreasing the efficiency of any portion of the heating-surface of the boiler, to adapt the invention 30 for wide furnaces, and generally to make the furnace as simple, effective, and inexpensive as possible.

I will now proceed to describe my invention with reference to the accompanying 35 drawings and will then point out the novel features in claims.

In the drawings, Figure 1 shows a longitudinal section of a water-tube boiler of the Babcock & Wilcox type employing longitudinal inclined generating-tubes, the furnace of which boiler is constructed in accordance 40 with my invention. Fig. 2 is a horizontal section of the setting of the said boiler, showing a top view of the arch and a section of the central support and air-conduit. Fig. 3 is a transverse section of the furnace, showing a construction of arch particularly applicable to wide furnaces.

My furnace comprises, as usual, a combus-

tion-chamber 1, an ash-pit 2, with suitable 50 fire-doors 3, ash-pit doors 4, grate-bars 5, and a bridge-wall 6 at the rear of the combustion-chamber. These parts may be of ordinary construction. The furnace has also the ordinary side walls 7. Above the furnace is 55 an arch 8, the construction of which is broadly claimed in the said application for Letters Patent filed October 10, 1901, Serial No. 79,176, of which this is a division, although a particular feature of the construction of the 60 arch is claimed herein. It has been common in the past to use arches over the combustion-chambers of furnaces; but such arches have usually been constructed of brick and have given much trouble by falling while the furnace is in use. The arch of my furnace is constructed of cantaliver-sections 9 9, of fire-clay or other suitable material, which in the case of furnaces of narrow or medium width may be set into the side walls 7, as illustrated 65 and described in my said application Serial No. 79,176; but in the case of wide furnaces, such as that illustrated in the drawings of this case, are preferably supported by skew-back supports 9', forming continuations of 70 the main cantaliver-sections 9, composed of similar material and set into the side walls. The reason for employing this construction in wide furnaces is that I find it difficult to obtain perfect and reliable arch-sections of a 75 greater length than three feet. The sections 9 are preferably joined at the center, as by an ordinary tongue-and-groove joint. Such an arch is exceedingly strong and will not be shaken down by jar or by vibration or by 80 the careless handling of fire-tools, as will a brick arch.

In order that space within the combustion-chamber may be economized, particularly at the center, where the most space is usually 85 needed, and in order that the arch-sections may have great strength in proportion to their thickness and weight, the said sections taper from their points of support at the sides to or nearly to the meeting-point at the center.

At the rear of the furnace there is the usual opening 10 for the escape of furnace-gases, and at the front of the furnace there is an-

other and preferably smaller opening 11, the existence of which is important, since otherwise the efficiency of the front portion of the boiler might be reduced. This is particularly true with respect to the type of boiler illustrated, in which the heating is effected mainly through the passage of the furnace-gases between and around the inclined generating-tubes 12 and along the under surface of the drum 13, the furnace for the sake of economy in space occupied being placed under the front portion of the boiler. In such boilers baffle-plates 14 are customarily used to deflect the furnace-gases from the rear of the combustion-chamber to the front portions of the generating-tubes and drum, thus making the front portions of these tubes and of the drum effective as heating-surface; yet in such boilers an arch over the combustion-chamber must inevitably prevent contact of the furnace-gases with the extreme front portions of the generating-tubes, and particularly of the lower tubes, unless an opening, such as 11, through which a portion of the furnace-gases may pass to these front portions of the generating-tubes, is provided.

In the front of the furnace-wall there is an air-flue 15, open at the ends. This flue communicates with flues in a projecting piece 16, which crosses the opening 11, so that air entering the flue 15 is discharged beneath but in close proximity to the lower portion of the arch and is caused to pass along the under surface of the arch, becoming heated as it does so, until it encounters the furnace-gases issuing through the opening 10 and assists in completing combustion in the furnace, and particularly in consuming the finely-divided particles of fuel, which otherwise might be smoke.

It is well known that if cold air be introduced into a furnace above the fuel perfect combustion may be interfered with rather than helped and the fire may be deadened; but I find the contrary to be the case when air, taken as above described, is highly heated, as above described, before encountering any considerable quantity of the furnace-gases. When such highly-heated air does encounter such gases, it aids materially in effecting complete combustion within the furnace.

Carrying the air from the flue 15 across the opening 11 by means of the flues in the block 16 prevents the air from becoming mixed at this point with the furnace-gases before the air has become highly heated. This block or projection also serves as a support for the arch. The sections 9 immediately above it rest upon it, and the adjacent sections are provided with inclined faces, so that the sections rest on one another, and thus the weight of sections distant from the support is transferred thereto. In the same manner a corbel-support 17, projecting from the bridge-wall, may be employed to support the arch at the rear. The width and depth of the combus-

tion-chamber determine whether one or more central supports for the arch shall be employed.

In the operation of the furnace the air entering through the flue 15 and projected along the under surface of the arch becomes highly heated, and then encountering the furnace-gases issuing through the opening 10 it supplies to such gases a relatively fresh supply of oxygen at a temperature such that combustion is greatly promoted thereby, and thus the greater portion of the unconsumed or incompletely-consumed gases and particles of fuel which otherwise might pass out of the chimney without being completely consumed are burned. Because of the opening 11 between the arch and the front of the furnace the front portion of the boiler is adequately heated, and thereby an objection to the employment of brick arches as heretofore constructed is overcome.

It will be noted that the invention does not involve the use of long and small flues through the arch, which are difficult to clean, nor does it involve the use of metal air-tubes, which are likely to be burned out. The air-flue in the front wall and the flues through the block 16 are relatively large and are easily cleaned by a steam-jet, and, moreover, the tendency of the air-current is to carry dust out of the flues rather than into them.

It is obvious that my invention is susceptible of many modifications in construction and arrangement of the parts and that many such modifications may be necessary to adapt it to furnaces of peculiar construction. I do not limit myself, therefore, to the particular details of construction and arrangement of parts herein illustrated and described.

What I claim is—

1. In a furnace, the combination with furnace-walls, an arch over the combustion-chamber, openings being provided at the front and rear of the arch for the escape of furnace-gases, and a baffle-plate which directs forward and over the arch the furnace-gases escaping through the said rear opening, of an air-flue which admits air beneath the arch and directs it along the lower surface thereof.

2. In a furnace, the combination with furnace-walls, of an arch over the combustion-chamber, an opening being provided at the front of the arch for the escape of a portion of the furnace-gases, and another opening being provided at the rear for the escape of the remainder of the furnace-gases, an air-flue at one end of the combustion-chamber for admitting air to the furnace, and means spanning one of said openings and containing a flue forming a continuation of such air-flue, for delivering air in the immediate vicinity of said arch.

3. In a furnace, the combination with furnace-walls, of an arch over the combustion-chamber, an opening being provided at the front of the arch for the escape of a portion of the furnace-gases, and another opening

provided at the rear for the escape of the furnace-gases, and a support for the arch, spanning one of said openings, and containing an air-flue which admits air beneath the arch 5 and directs it along the lower surface thereof.

4. In a furnace, the combination with furnace-walls, of an arch over the combustion-chamber comprising skewback supports supported and projecting from the furnace-walls 10 and forming part of the span of the arch, and

main cantaliver-sections extending from the center to the ends of the said skewbacks but not to said side walls, supported by said skewbacks and joined at the center.

In testimony whereof I affix my signature 15 in the presence of two witnesses.

WILLIAM F. WILMOTH.
